UNITED STATES PATENT OFFICE.

FRIEDRICH CARL KRÜGER, OF HANOVER, GERMANY.

ENGINE HAVING ROTARY PISTON.

968,859.

Specification of Letters Patent. Patented Aug. 30, 1910.

Application filed March 12, 1908. Serial No. 420,691.

To all whom it may concern:

Be it known that I, FRIEDRICH CARL KRÜGER, a subject of the German Emperor, and resident of Hanover, Germany, have invented certain new and useful Improvements in Extensible Piston-Wings for Engines Having Rotary Pistons, of which the following is a specification.

This invention relates to improvements in engines or pumps having rotary pistons. The pistons of these engines usually are equipped with elements, which in the rotation of the piston engage the entire interior surface of the cylinder, and which are adapted to obtain a constant steamtight division of one half of the cylinder from the other.

Objects of the invention are to provide an arrangement of these elements, so that they expand in more than one direction, and thus at all times frictionally engage the inside wall of the cylinder and the portions of the piston wherein they are guided.

In the drawing: Figure 1 shows an embodiment of my invention with a rotary piston in a cylinder in side elevation. Fig. 2 is a plan view of the same with parts in section. Fig. 3 shows another embodiment of my invention with a rotary piston in a cylinder in side elevation. Fig. 4 is another plan view of the same with parts in section.

The engine comprises a casing, a rotary piston and a shaft, the rotary piston being keyed to the shaft and mounted eccentrically within the cylinder casing. Elements are provided for engaging the inside surface 3 of the cylinder and they may comprise in combination four parts 1, 2, 5 and 6 and a packing strip 4. The structure comprising the parts 1, 2, 5 and 6 constitutes a "piston wing" and two of these wings are provided on the piston, one diametrically opposite to the other. The packing strip 4 extending over the entire length of the cylinder has substantially semicircular cross section and rests in a correspondingly shaped groove of the wing parts 1 and 2. When the piston rotates and the wing is pressed in radial direction against the cylinder wall the packing strip 4 will slide over the entire interior surface 3. The wing parts 1, 2, 5 and 6 are wedge shaped, parts 1 and 2 with their inclined sides being placed on the inclined side of parts 5 and 6, so that the upper and lower faces of the thus combined wing are parallel to each other, forming a substantially prismatic element, adapted to slide in

a radially arranged chamber 8 of the piston. The juxtaposed wing parts 1 and 2, 5 and 6 respectively, do not abut against each other, so that gap 12 and gap 17 respectively are formed between them. The gaps 12 and 17, as may be seen from Fig. 2, are out of alignment with each other and are closed by means of members 20 and 21, which slide in suitably shaped recesses provided in the wing parts. Gap 12 is also closed by a wedge 7 engaging the packing strip 4. Those parallel edges of wing parts 1 and 2, which are disposed next to the piston hub and which are separated from each other by the gap 12, are beveled, so that a substantially V-shaped notch 22 is formed between them.

A gas or liquid pressure forcing the wings radially outwardly against the cylinder wall is maintained in the chamber 8, and in the embodiment illustrated in the drawing this pressure is obtained by admitting steam or some other medium through pipe 10 into one of the annular chambers 9, which communicates with the radially arranged chambers 8 and through them with the other annular chamber 9. The pressure in radial direction is transmitted directly to the wing and as soon as the wing 4 is forced radially outwardly to the limit of its movement the pressure spreads the wing elements against the guiding sides of the chamber 8.

The wing parts 5 and 6 are shaped so that their thickness increases toward the hub, they therefore present a larger surface to the radial pressure than the wing parts 1 and 2. In addition to this they are provided with preferably integrally formed lugs 24 and 25 respectively, and a member 11 slides in suitably shaped recesses of these lugs. Any radial pressure exerted upon the parts 5 and 6 or the member 11 will effect relative displacement of the wing elements 1, 5 and 2, 6 and therefore increase the friction between the wing and the upper and lower walls of the chamber 8 until an absolutely steamtight engagement of these parts is attained. The member 11 is provided with a preferably integral wedge shaped lug 23 engaging the V-shaped groove 22, and a radial pressure exerted upon the member 11 will therefore tend to increase the distance between the wing parts 1 and 2, forcing them apart and against the opposite covers of the cylinder. Dowel pin 14 secured to the wing part 5 and engaging slot 13 in wing part 1,

and dowel pin 16 on wing part 6 engaging slot 15 in wing part 2 serve for the purpose of transferring the last described motion of the wing parts 1 and 2 to the wing parts 5 and 6 respectively.

In the embodiment illustrated in Figs. 3 and 4 the expansion against the two opposite cylinder covers is attained in a different way. The member 11 slidably carried by the lugs of the wing parts 5 and 6 is between these lugs provided with a raised portion, into which recesses are cut. These recesses converge radially. Lug 18 provided on wing part 2 and lug 19 on wing part 1 are slidably seated within these grooves, and a pressure in radial direction against the member 11, will cause the wing parts 1 and 2, if they are prevented from following the direction of the pressure, to move toward the opposite covers of the cylinder. The movement is transferred to the wing parts 5 and 6 by dowel pin and slot connection designated with the same reference letters as in Figs. 1 and 2.

Having now fully described my said invention what I claim and desire to secure by Letters Patent is:—

1. In a rotary engine the combination with a cylinder, of a piston drum provided with a radial chamber extending longitudinally through said drum, four juxtaposed and superposed wing parts arranged by pairs within said chamber, the upper pair of said wing parts being in wedging engagement with the lower pair, lugs carried by one pair of said wing parts, a member in coaction with said lugs and in engagement with the other pair of wing parts, said member being adapted to displace said other wing parts longitudinally with respect to the drum, under the pressure of steam in said radial chamber and means for admitting steam into said chamber.

2. In a rotary engine the combination with a cylinder, of a piston drum provided with a radial chamber extending longitudinally through said drum and an annular chamber communicating with said radial chamber, four juxtaposed and superposed wing parts arranged by pairs within said radial chamber, the upper pair of said wing parts being in wedging engagement with the lower pair, lugs carried by one pair of said wing parts, a member in coaction with said lugs and in engagement with the other pair of wing parts, said member being adapted to displace said other wing parts

simultaneously in opposite direction longitudinally with respect to said drum under the pressure of steam in said radial chamber and means for admitting steam into said annular chamber.

3. In a rotary engine the combination with a cylinder, of a piston drum provided with a radial chamber extending longitudinally through said drum and an annular chamber communicating with said radial chamber, four juxtaposed and superposed wing parts arranged by pairs within said radial chamber, the juxtaposed parts of each pair being separated by a gap, the gaps of said pairs being out of alinement with each other, elements transversely disposed with respect to said gaps and slidable in each of said parts, pins projecting from the parts of one pair into slots provided in the parts of the other pair in superposition, lugs carried by one pair of said wing parts, a member in coaction with said lugs and in engagement with the other pair of said wing parts, said member being adapted to displace said other wing parts longitudinally with respect to said drum, under the pressure of steam in said radial chamber, and means for admitting steam into said annular chamber.

4. In a piston drum for rotary engines the combination with a chamber radially arranged in the said drum and a piston wing slidably engaged into the said chamber and composed of four juxtaposed and superposed parts arranged by pairs in wedging engagement with each other, of a second chamber arranged behind the said piston wing, means for introducing a pressure fluid in the said chamber, laterally directed guide on the rear surface of each of the parts of one pair of said wedging members, a wedge slidably engaged into the said guides, a miter projection arranged on the said wedge and adapted to engage from the rear the gap left between the other pair of wedging members of the wing, so as to force the said members apart and a tongue and groove connection between the two pairs of wedging members adapted to transmit the separating motion from one pair of members to the other pair, substantially as and for the purpose set forth.

In testimony whereof I have hereunto set my hand in presence of two witnesses.

FRIEDRICH CARL KRÜGER.
